DESIGN FOR A DRESS

Rose Feintuck, New York, N. Y.

Application July 7, 1937, Serial No. 70,296

Term of patent 3½ years

To all whom it may concern:

Be it known that I, Rose Feintuck, a citizen of the United States of America, residing in Manhattan, county of New York, and State of New York, have invented a new, original, and ornamental Design for a Dress, of which the following is a specification, reference being had to the accompanying drawing, forming part thereof, wherein,

The design is characterized by the combination on the dress as shown, of the sunburst arranged tucks on the sleeves and rear waist portion and radiating from contrastingly colored bows, as shown.

I claim:

The ornamental design for a dress, substantially as shown, and described.

ROSE FEINTUCK.
